SPARK PLUG

Guy F. Wetzel, Park Ridge, Ill.

Application January 15, 1949, Serial No. 71,158

3 Claims. (Cl. 123—169)

1

This invention relates to spark plugs and constitutes an improvement over the invention disclosed in my copending application, Serial No. 22,157, filed April 20, 1948, now abandoned.

The spark plugs of said copending application and of the present application include certain standard elements such as a grounded shell and insulated ignition electrode and a grounded electrode, together with one or more auxiliary electrodes which are also grounded.

One of the objects of the present invention is the provision of grounded electrodes of novel construction.

The invention includes a plurality of grounded electrodes as referred to above; one of the grounded electrodes cooperates with the insulated electrode to form a spark gap and the remaining or auxiliary electrode or electrodes direct a high frequency discharge or corona effect into the spark gap.

Another object of the invention is the provision of grounded electrodes as referred to above, arranged in such manner that because of the high frequency discharge the spark occurs more readily and propagates faster through the combustion mixture.

Another object of the invention is the provision of grounded electrodes as referred to, arranged in a novel manner so as to give as free a path as possible to the ionized gas caused by the high frequency discharge in the combustion mixture, and as a consequence thereof rapid propagation of combustion is accomplished; as a corollary to this object, the grounded electrodes are arranged so that there is a minimum of shielding of the spark in the spark gap with the result that the spark or flame propagates rapidly through the combustion mixture.

A further object is the provision of grounded electrodes which are flat with narrow edges and are so arranged that the narrow edges are disposed adjacent the insulated electrode so that the spark and the high frequency discharge have greater efficiency.

A still further object of the invention is the provision of flat grounded electrodes so arranged as to create a greater turbulence of the combustion mixture due to their positioning with their flat sides facing in the directions of normal movement of currents of the mixture.

Another object of the invention is the provision of two or more grounded electrodes so arranged that one of them cooperates with the insulated electrode for causing a spark and the other grounded electrode produces a high frequency

2

discharge, and with the further provision that the two grounded electrodes more or less, alternately become the ignition and auxiliary electrodes respectively.

5. A still further object of the invention is the provision of a spark plug for carrying out the objects referred to above which can be produced by ordinary manufacturing methods and without the necessity of extreme accuracy.
10. Still another object is the provision of a spark plug by means of which cleaner firing action is accomplished as well as easier starting of the engine whether hot or cold.

With these and other objects in view, my invention consists in the construction, arrangement and combination of the various parts of my device whereby the objects contemplated are attained as hereinafter more fully set forth, pointed out in the claims and illustrated in the accompanying drawings in which:

Figure 1 is an elevational view of the spark plug embodying the present invention;

Figure 2 is an enlarged view of the lower part of Figure 1 with a portion thereof shown in section;

25. Figure 3 is a bottom view of Figure 2;

Figure 4 is a view taken on line 4—4 of Figure 2;

Figure 5 is an enlarged detailed view of the electrodes graphically illustrating the action between the electrodes;

Figure 6 is a view similar to Figure 5 showing one of the grounded electrodes partially eaten away and the respective actions of the grounded electrodes thereby reversed; and

35. Figure 7 is a view of a portion of a spark plug showing a modified form of grounded electrodes.

Referring now in detail to the drawings, the reference numeral 12 indicates generally a spark plug which for the most part is a standard plug. The details of construction of the main part of the plug need not be dwelt upon except to point out that the plug includes a metallic shell 14 adapted to be threaded into a spark plug opening in an engine. The shell 14 is thereby electrically grounded with the frame of the engine. The spark plug includes a central ignition electrode 16 which is insulated by means of an insulator 18 from the shell 14 and is provided with a terminal 20 for connection with the ignition circuit of an automobile.

The grounded electrodes are designated by the numerals 24 and 26. The grounded electrodes 24 and 26 are substantially identical with each other and each comprises a flat relatively thin strip of

material. The material of the grounded electrodes is any preferred alloy adapted for the purpose. The electrodes 24 and 26 may be connected in any suitable manner to the shell 14, the latter having as usual an annular lower end. One way of securing the electrodes 24 and 26 to the shell 14 consists in electrically welding the electrodes thereto as illustrated in Figure 2. Thus, there is an electrically grounded connection between the electrodes and the shell. It will be understood that other means may be employed for securing the electrodes 24 and 26.

The grounded electrodes 24 and 26 are then bent toward each other as illustrated in the various figures. The discharge ends of the electrodes are then twisted so that the flat sides thereof are disposed vertically or in planes extending longitudinally of the insulated electrode 16. The spark plug will at times be referred to as having a lower end, but it will be understood that this expression refers to vertical positioning of the plug, and is to be interpreted according to the relative position in which the spark plug will be inserted in the engine.

The numeral 28 indicates the discharge ends of the grounded electrodes 24 and 26. The discharge ends are disposed adjacent each other forming a gap 30 therebetween. As illustrated, the gap 30 extends longitudinally of the insulated electrode 16 and this gap is relatively small or on the order of from .010" to .025"; however, I do not wish to be limited to any exact size of gap. A comparison of Figures 2 and 3 will show that the discharge ends 28 of the grounded electrodes have a relatively long and a relatively short transverse dimension or as stated above they are generally flat and thin. The narrow edges of the discharge ends, or the edges across the narrow dimension, are disposed adjacent the lower end of the insulated electrode 16 forming therewith a gap as indicated at 32. The gap 32 may be of a dimension similar to the usual spark gap in standard spark plugs. However, the relative length of gap between the insulated electrode 16 and each grounded electrode is important in understanding the present invention. Figures 5 and 6 illustrate in exaggerated form that the gaps between the grounded electrodes and the insulated electrode are considerably different, namely, the gap between the grounded electrode 26 and the insulated electrode is greater than the gap between the grounded electrode 24 and the insulated electrode. The difference in length of these two gaps is only that difference brought about by very slight inaccuracies in the dimensions of the electrodes or in the forming process. For all practical purposes and as judged by the naked eye there is no difference between the lengths of these two gaps; however, due to the fact that articles such as electrodes are never perfect, there is a very slight difference in the lengths of the two gaps and this difference is usually only minor.

Figure 5 shows the electrode 26 closer to the insulated electrode 16 and as a result thereof a spark gap is set up between these two electrodes. The solid lines 34 graphically illustrate that a spark takes place between the electrodes 24 and 16. The discharge end of the electrode 26 is spaced a greater distance from the insulated electrode 16 and as a consequence there is no spark created between these electrodes. The dotted lines 36 illustrate graphically a high frequency discharge or corona effect emitted from the grounded electrode 26.

As pointed out in the copending application referred to above, this phenomenon is not too well known, but it is known that there is some form of discharge. The discharge is invisible to the naked eye in the dark, but I have shown that the effects of the discharge can definitely be determined.

The spark occurring across the two electrodes 24 and 16 eventually causes some loss of metal from the electrode 24 due to electrical erosion. This is illustrated by the cut-out portion 38. The upper point of the electrode 24 will then eventually be spaced at a greater distance from the electrode 16 than the electrode 26 will be. Therefore, the spark occurs across the electrodes 26 and 16 which then become the ignition electrodes. The electrode 24 then becomes the auxiliary electrode and the high frequency discharge or corona effect will be emitted from the electrode 24 as illustrated in Figure 6.

Figure 7 illustrates a modified form of grounded electrode. In this instance the grounded electrodes are indicated at 40 and 42. The outer ends of these electrodes are of round wire which can be inserted by a press fit in holes in the shell of the spark plug, or electrically welded thereto. The discharge ends of the electrodes are flattened as illustrated at 44, and are bent toward each other as in the previous embodiment. Thus, the discharge ends of the electrodes 40 and 42 are similar to and arranged in a manner similar to electrodes 24 and 26, but formed from different shaped material.

Thus, two grounded electrodes are provided and as far as manufacturing methods are concerned they are identical; however, either one of them may become an ignition electrode and the other an auxiliary electrode and their relationship will be reversed from time to time.

The high frequency discharge enters into the immediate area of the spark gap with the result that the fuel in that area is disturbed and desirable turbulence is created in the spark zone. As a result of this action, the spark becomes more effective, and combustion of the fuel accordingly becomes more efficient. The action may be compared generally with disturbing the fire and creating a greater front to the fire or combustion and enabling it to propagate faster.

The arrangement of the electrodes with their relatively narrow edges disposed adjacent the insulated electrode 16 and their flat sides extending longitudinally thereof, provides as wide a path as possible for the propagation of the combustion caused by the spark with a minimum of shielding or blanketing. The propagation of the spark is generally downwardly and divergent, and as illustrated in Figure 4 it will be seen that the grounded electrode 26 presents as small a surface as possible toward the insulated electrode, or in other words as great a space or path as possible is arranged so that the spark and combustion may readily propagate through the combustion chamber. The arrangement of the grounded electrodes is also such that the corona effect or high frequency discharge creates as turbulent effect as possible because of the fact that it is permitted to emerge sidewise from the immediate area of the spark as well as directly into the spark gap. The high frequency discharge agitates the combustion mixture to a considerable distance with the result that combustion propagates rapidly therethrough.

A further advantage of the arrangement of the grounded electrodes 24 and 26 resides in the ef-

fect they have in creating additional mechanical turbulence in the combustion mixture. The stroke of the piston and design of cylinder head sets up a turbulence or currents in the combustion chamber, and at the top thereof the combustion mixture normally travels horizontally more so than vertically. This horizontal movement results in the currents striking the flat sides of the grounded electrodes whereby a greater turbulence is set up in the gases of the combustion mixture. This is particularly true in the case of the electrode portions 28 of Figure 2 and 44 of Figure 7, although the upper portions of the electrodes 24 and 26 of Figure 2 that are secured to the shell are effective in causing turbulence in the gases travelling horizontally against their flat sides. The increase in turbulence has an advantageous effect in the propagation of the spark or flame throughout the combustion mixture as referred to above.

It will be understood that the number of the grounded electrodes need not be limited to two, but may be three or more in number. In any case only one of the grounded electrodes will become an ignition electrode and form a spark gap with the insulated electrode.

It will be thus evident that I have produced a novel spark plug which has a number of important advantages over conventional plugs among which are easier starting of cold engines; cleaner firing action whereby the plug will operate efficiently under conditions which cause conventional plugs to fail because of fouling; and more effective sparking which causes the engine to run better. Because of the clean firing of the spark plug of the present invention it can be used about two numbers colder than conventional plugs.

Spark plugs embodying the present invention have been used in automobiles run over 10,000 miles with no appreciable deterioration, and the spark plug keeps much cleaner than conventional spark plugs.

It will be seen from the above that I have produced an effective spark plug which is simple to manufacture and although having numerous advantages is sufficiently like the conventional spark plug so that it can be made at low cost and therefore is a commercially practical spark plug.

While I have herein shown and described a particular embodiment of my invention, it will be understood of course that I do not wish to be limited thereto since many modifications may be made, and I therefore contemplate by the appended claims to cover any such modification or substitution of mechanical equivalents as fall within the true spirit and scope of my invention.

I claim:

1. A spark plug comprising a grounded shell, a central ignition electrode insulated from said shell, and a plurality of electrodes grounded to said shell, said grounded electrodes being rigid and fixed with respect to said shell and to said insulated electrode, the discharge ends of said grounded electrodes being bent toward each other into positions longitudinally beyond said insulated electrode, said discharge ends being flat and having a relatively long and a relatively short transverse dimension, said long transverse dimension extending longitudinally of said insulated electrode, and said flat sides being thereby disposed in planes parallel with the longitudinal axis of said insulated electrode, said discharge ends forming a gap with said insulated electrode longitudinally beyond the latter, said discharge ends forming a relatively narrow gap between

themselves in a position longitudinally beyond said insulated electrode, said discharge ends being close together and thereby forming an effectively continuous flat surface of substantial transverse dimension for baffling combustion mixture flowing in directions transverse to said planes.

2. A spark plug comprising a grounded shell, a central ignition electrode insulated from said shell, and a plurality of electrodes grounded to said shell, said grounded electrodes being rigid and fixed with respect to said shell and to said insulated electrode, said grounded electrodes being of flat material having a relatively long and a relatively short transverse dimension, the ends of said grounded electrodes secured to said shell being positioned with their long transverse dimension disposed generally peripherally of said shell, the discharge ends of said grounded electrodes being bent toward each other into positions longitudinally beyond said insulated electrode, said discharge ends being disposed with their long transverse dimension extending longitudinally of said insulated electrode, the flat sides of said discharge ends being thereby disposed in planes parallel with the longitudinal axis of said insulated electrode, said discharge ends forming a gap with said insulated electrode longitudinally beyond the latter, said discharge ends being close together and thereby forming an effectively continuous flat surface of substantial transverse dimension for baffling combustion mixture flowing in directions transverse to said planes.

3. A spark plug comprising a grounded shell, a central ignition electrode insulated from said shell, and a plurality of electrodes grounded to said shell, said grounded electrodes being rigid and fixed with respect to said shell and to said insulated electrode, the ends of said grounded electrodes secured to said shell being of substantially round stock, the discharge ends of said grounded electrodes being bent toward each other into positions longitudinally beyond said insulated electrode, said discharge ends being flat and having a relatively long and a relatively short transverse dimension, said long transverse dimension extending longitudinally of said insulated electrode, and said flat sides being thereby disposed in planes parallel with the longitudinal axis of said insulated electrode, said discharge ends forming a gap with said insulated electrode longitudinally beyond the latter, said discharge ends forming a relatively narrow gap between themselves in a position longitudinally beyond said insulated electrode, said discharge ends being close together and thereby forming an effectively continuous flat surface of substantial transverse dimension for baffling combustion mixture flowing in directions transverse to said planes.
